UNITED STATES PATENT OFFICE.

JOHN N. POWERS, OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

DETONATING-FUSE.

1,224,414.

Specification of Letters Patent.

Patented May 1, 1917.

Application filed February 14, 1916. Serial No. 73,130.

To all whom it may concern:

Be it known that I, JOHN N. POWERS, a citizen of the United States, residing at Washington, District of Columbia, have invented 5 certain new and useful Improvements in Detonating-Fuses; and I do hereby declare the following to be a full, clear, and exact description of the invention, such as will enable others skilled in the art to which it applies 10 to make and use the same.

My invention relates to detonating fuses for high explosive projectiles.

It is my purpose to provide an improved construction of detonating fuse which will 15 assure certainty of action, absolute safety in storing projectiles, absolute safety in handling projectiles, safety from deterioration, and delayed action in penetration.

It is my further purpose to simplify the 20 construction and assembling of fuses of this type by embodying therein two structurally independent self-contained elements as follows: first, a guide tube and barrier mechanism; second, a detonative compound container housing and barrier mechanism, the latter being removably mounted in the rear end of the fuse stock so that it is unnecessary to associate the detonating charge with the fuse until it is desired to fire the projectile. 25 By such a construction I obtain absolute safety in handling and storing projectiles and am enabled to keep the detonating charge in an isolated store until required for use.

I will describe my invention in the best 30 form known to me at present, but it will be apparent that it is susceptible to changes in details, proportions and arrangement with the exercise of only ordinary mechanical skill without departing from the spirit of the invention.

In the drawings chosen to illustrate my invention, the scope whereof is set forth in the claims.

Figure 1 is a longitudinal section of a detonating fuse constructed in accordance with my invention, a fragment of an associated projectile being shown;

Fig. 2, a section on the line 2—2 of Fig. 1; 45 Fig. 3, a view of a fragment of what is

shown in Fig. 1 with the parts in the position they would occupy upon impact of the projectile;

Fig. 4, a view similar to Fig. 2, the status of the parts being that shown in Fig. 3;

Fig. 5, a section on the line 5—5 of Fig. 1;

Fig. 6, a section on the line 6—6 of Fig. 1;

Fig. 7, a section on the line 7—7 of Fig. 1;

Fig. 8, a section on the line 8—8 of Fig. 1;

Fig. 9, a perspective view of one of the 60 barrier levers and its associated barrier section, and

Fig. 10, a perspective view of one of the centrifugally released locking arms.

Referring to the drawings my improved 65 detonating fuse is shown as comprising a tubular stock 15 which carries the various parts of the fuse and is threaded in the base of the projectile, the latter being indicated at A. Threaded in the forward end of the 70 stock 15 is a nose 16 which projects slightly beyond the adjacent end of the stock so as to protrude into the bursting charge of the projectile. This nose 16 is provided with a reduced extension 17 on its rear end and 75 further provided with a longitudinal recess 18 opening through the rear of the nose and enlarged as at 19 to form a shoulder 20. The forward wall of the recess 18 is provided with a firing pin or point 21, the purpose of 80 which will presently appear. Threaded in the recess 18 is a tube 22 which in conjunction with the nose 16 forms the fuseway or guide tube of the fuse. The rear end of the tube 22 is enlarged as at 23 and this enlarged portion is provided with diametrically opposite longitudinal grooves 24. The rear end of the enlarged portion 23 is provided with a transverse groove 25 the longitudinal axis of which intersects the longitudinal axes of the grooves 24. Pivoted in each groove 24 is a barrier lever 26 and pivoted to the free end of each lever 26 is a barrier section 27 slidable in the groove 25. Each lever 26 is provided with an outwardly 95 extending tail portion 28 forming a cam face 29. Movably mounted on the tube 22 and surrounding the enlarged portion 23 of said tube is a slide 30. The forward end of this slide snugly fits the minor portion of the 100

tube 22 and limits the movement of the slide in one direction by engagement with the adjacent end of the enlarged portion 23. Formed in the slide 30 are diametrically opposite slots 31 disposed in the plane of movement of the levers 26 and through which the levers are adapted to be moved when the barrier sections 27 are operated to either opened or closed positions. Each of the slots 31 is traversed by a bridge 32 of triangular cross section and forming a cam face 33 adapted to coöperate with the adjacent cam face 29 of the related lever 26 during movement of the slide 30 in one direction. The slide 30 is normally held in the position shown in Fig. 1 by means of a spring 34 which seats against the shoulder 20 and against the adjacent end of the slide. In the normal position of the slide the barrier sections 27 are held in closed position and the interior of the tube 22 isolated from the other fuse parts to be hereinafter referred to. The slide 30 is also provided with diametrically opposite longitudinal grooves 35 and pivoted in the rear ends of these grooves respectively are the corresponding ends of centrifugally released locking arms 36. Each arm 36 carries a spring 37 which bears against the stock 15 and normally holds the free end of the related arm interposed between the nose 16 and the slide 30 so that the latter is locked against movement in the direction of the nose. The diameter of the slide 30 and the rear end 17 of the nose 16 is somewhat less than the diameter of the corresponding portion of the bore of the stock so that an air chamber 38 is formed. This chamber is placed in communication with the forward end of the recess 18 by a plurality of passages 39 formed in the nose 16. In order that the forward end of the nose 16 will be readily ruptured when the fuse is fired I weaken same through the medium of a plurality of grooves 40.

It will be noted that the nose 16, tube 22 and barrier mechanism previously described constitute a self-contained element adapted to be assembled independent of the stock 15 and then applied within the latter as a whole. By such construction I greatly simplify the manufacture of a fuse of this type and introduce into it a factor greatly enhancing the safety in handling and storing projectiles equipped with such fuses.

My improved fuse further embodies a detonative compound container housing 41 detachably threaded in the bore of the stock 15. This housing is provided with an axial recess 42 opening through its forward end and further provided with diametrically opposite longitudinal recesses 43 also opening through the forward end of the housing. A transverse passage 44 is also provided in the housing 41 and the ends thereof are enlarged to form pairs of shoulders 45 and 46. Mounted in the passage 44 are barrier sections 47 and 48 which are normally held in position to close the recess 42 and thereby isolate the detonative compound container 49 which is mounted in said recess and secured to the housing by the usual shearing pin 50. The barrier section 47 has its outer edge provided with a recess 51 and secured to the section 47 at the base of this recess through the medium of a screw 52 is the central portion of a leaf spring 53 the ends of which seat on respective shoulders 46. The barrier section 47 is normally held in closed position by a spring pressed bolt 54 mounted in one of the recesses 43 and having its forward end engaged over the outer edge of said section. It will be observed that when the section 47 is held in closed position by the bolt 54 the spring 53 is tensioned so that the instant the bolt 54 is moved out of engagement with the section 47 the spring 53 will operate to move said section to open position. The mechanism for holding the barrier section 48 normally in closed position is identical with that described with reference to the barrier section 47 and will not be referred to in detail but the reference characters employed in describing the mechanism associated with the barrier section 47 will be applied to corresponding parts of the mechanism associated with the barrier section 48.

It will also be noted that the housing 41, detonative compound container 42 and the barrier mechanism carried by the housing 100 constitute a self-contained element adapted to be assembled independently of the stock and subsequently applied thereto as a whole. Such a construction also introduces another factor of safety in the fuse in that the detonating charge can be kept in an isolated store and only applied in the stock 15 when it is desired to fire the projectile.

The operation of the fuse will be obvious. When the projectile containing the fuse is fired the bolts 54 will set back and the springs 53 will operate to move the barrier sections 47 and 48 to open position. Centrifugal force due to the rotation of the projectile in flight will move the arms 36 to 105 release position against the influence of the springs 37. Upon impact of the projectile with the target or other object the slide 30 will move forward and cause the cam faces 33 to coact with the cam faces 29 and thus move the levers 26 to shift the barrier sections 27 to open position. At the same time the impact of the projectile will shear the pin 50 and drive the detonative compound container 49 forward through the tube 22 125 and into the recess 18 where its primer will

engage the firing point 21 to explode the container and thus fire the bursting charge of the projectile.

What is claimed is:—

5. 1. In a detonating fuse for high explosive projectiles, the combination of a fuse stock, a guide tube element independent of and mounted in one end of the stock, a housing element independent of and mounted in the 10 other end of the stock, a detonative compound container in the housing element in line with the guide tube, a normally closed barrier constantly carried by one of said elements and interposed between the container and guide tube, and automatically operated means for opening the barrier.

2. In a detonating fuse for high explosive projectiles, the combination of a fuse stock, a guide tube secured in one end of the stock, 20 a detonative compound container disposed in the stock in line with the guide tube, a barrier normally closing the end of the guide tube adjacent the container, and impact operated means for opening the barrier.

25. 3. In a detonating fuse for high explosive projectiles, the combination of a fuse stock, a guide tube independent of and mounted in one end of the stock, a housing independent of and mounted in the other end of the 30 stock, a detonative compound container in the housing in line with the guide tube, a normally closed barrier carried by the housing and interposed between the container and guide tube, and automatically operated 35 means for opening the barrier.

4. In a detonating fuse for high explosive projectiles, the combination of a detonative compound container housing adapted to be secured in the projectile, an automatically 40 opened barrier carried by and normally closing the housing, a guide tube adapted to be secured in the projectile independently of and in advance of the housing, and an automatically opened barrier carried by and 45 normally closing the guide tube.

5. In a detonating fuse for high explosive projectiles, the combination of a fuse stock, a guide tube mounted in one end of the stock, a detonative compound container disposed 50 in the stock in line with the guide tube, a barrier normally closing the end of the guide tube adjacent the container, impact operated means for opening the barrier, and centrifugally released means normally locking the 55 impact operated means inactive.

6. In a detonating fuse for high explosive projectiles, the combination of a fuse stock, a guide tube mounted in the fuse stock, a detonative compound container disposed in 60 the stock in line with the guide tube, a nor-

mally closed barrier interposed between the container and the advance end of the guide tube, and impact operated means for opening the barrier.

7. In a detonating fuse for high explosive 65 projectiles, the combination of a fuse stock, a guide tube secured in one end of the stock, a detonative compound container disposed in the stock in line with the guide tube, a normally closed barrier between the guide 70 tube and container, and impact operated means for opening the barrier.

8. In a detonating fuse for high explosive projectiles, the combination of a fuse stock, a guide tube secured in said stock having its 75 outer end closed and its inner end reduced to form an air chamber between same and the stock, said tube further having air passage therein communicating at one end with the forward end of the tube and at their 80 other ends with said air chamber, a detonative compound container disposed in the stock in line with the tube, a barrier normally closing the guide tube in advance of the container, and automatically operated 85 means for opening the barrier.

9. In a detonating fuse for high explosive projectiles, the combination of a fuse stock, a guide tube mounted in the stock, barrier levers pivoted to said tube, barrier sections 90 carried by the levers respectively, a sliding member on the tube normally coöperating with the barrier levers to hold same in position to dispose the barrier sections closed and adapted when moved by impact to operate the levers to a position to dispose the barrier sections open, and a detonative compound container mounted in the stock in 95 line with the guide tube.

10. In a detonating fuse for high explosive 100 projectiles, the combination of a stock, a guide tube independent of and mounted in said stock and having a closed outer end, an automatically opened barrier mechanism constantly carried by the tube and normally 105 closing the inner end thereof, a detonative compound container housing independent of and mounted in the stock with its container chamber in line with the guide tube, an automatically opened barrier mechanism constantly carried by the housing and normally 110 closing the container chamber, and a detonative compound container in the chamber of the housing.

In testimony whereof I affix my signature, 115 in the presence of two subscribing witnesses.

JOHN N. POWERS.
